CHILD'S GARMENT

Filed Dec. 21, 1929

UNITED STATES PATENT OFFICE

HARRY KATZ, OF PHILADELPHIA, PENNSYLVANIA, ASSIGNOR TO MOSES WERTHEIMER,
OF PHILADELPHIA, PENNSYLVANIA

CHILD'S GARMENT

Application filed December 21, 1929. Serial No. 415,811.

This invention relates to a child's garment of the romper type and has for its object to provide, in a manner as hereinafter set forth, an article of such class which can be worn as an outer garment for child's use when desired or as an undergarment in combination with an outer garment, such as a child's dress, thereby providing a two-piece suit and overcoming the necessity of the child wearing a separate underwaist and a separate pair of drawers, as is the case at present, and with the underwaist detachably connected with the drawers.

A further object of the invention is to provide, in a manner as hereinafter set forth, a child's garment of the romper type which can be manufactured at a materially less expense than that now required in the production of the form of children's rompers now in general use.

A further object of the invention is to provide, in a manner as hereinafter set forth, a child's garment formed of a series of sections and with the sections providing for the manufacturing of the garment at a materially less expense than that now required in the production of the form of similar garments now in general use.

Further objects of the invention are to provide, in a manner as hereinafter set forth, a child's garment of the romper type which is simple in its construction and arrangement, strong, durable, thoroughly efficient in its use for the purpose intended, and inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claim hereunto appended.

In the drawings wherein like reference characters denote corresponding parts throughout the several views:—

Figure 1 is a front elevation of a child's

garment in accordance with this invention.

Figure 2 is a rear elevation thereof.

Figure 3 is an elevation of one of the sections of the front of the garment.

Figure 4 is a section on line 4—4, Figure 1. 55

Figure 5 is a section on line 5—5, Figure 1.

Figure 6 is a section on line 6—6, Figure 2.

Figure 7 is a section on line 7—7, Figure 1.

A child's garment in accordance with this invention includes a front and a back referred to generally at 1, 2 and a pair of extension members 3, 4 connected throughout to the front 1 and further connected at spaced portions thereof, to the back 2. The front 1 is formed from a pair of oppositely disposed sections 5, 6 of like contour. The back is set up from a pair of oppositely disposed upper sections 7, 8 of like contour and a lower section 9 which is of a width which corresponds substantially to the combined width of sections 7, 8. The combined width of sections 5, 6 is greater than the combined width of sections 7, 8, as well as the width of section 9. 70

Each of the sections of the front 1 is of a length equal to the combined length of sections 7 and 9 or sections 8 and 9 when sections 7, 8 and 9 are set up relatively to each other and with respect to sections 5, 6. Each of the sections of the front 1 is to be of the desired width and is formed with top and bottom edges and inner and outer side edges and with the top edge of less length than the bottom edge and with the side edges of materially greater length than the top and bottom edges. The bottom edge is squared throughout as indicated at 10. The top edge designated 11 inclines downwardly from its inner end 12 to its outer end 13. 75

The inner end 12 of the edge 11 is not in alignment with the inner end 14 of the edge 10, but is positioned beyond such end. The inner end 12 of the edge 11 is positioned inwardly with respect to the outer end 15 of the edge 10. The inner side edge of the section has a squared, intermediate portion 16, an inwardly curved upper portion 17 and a lower portion having a part thereof squared as at 18 and the remaining part curved as at 19. 80

The intermediate portion 16 of the inner side 85

90

95

100

edge is of materially greater length than the upper and lower portions of such edge. The ends 12 and 14 of the edges 11 and 10 respectively are arranged outwardly with respect to the intermediate portion of the inner side edge. The curved upper portion of the inner side edge extends from the upper end 20 of the intermediate portion 16 of such edge and terminates in the inner end 12 of the top edge 11. The curved part 19 of the lower portion of the inner side edge extends from the lower end 21 of said intermediate portion 16 and terminates in the squared portion 18 of such lower portion of the inner side edge, and said squared part 18 terminates in the inner end 14 of the edge 10. The outer side edge of the section is formed of two curved parts indicated at 22, 23 and with the latter of greater length than the former. The curved part 22 extends upon a forwardly directed curve from the outer end 13 of edge 11 to the upper end of the curved part 23 of the outer edge. The curved part 23 is upon an inwardly and outwardly directed curve and extends from the lower end of part 22 to the outer end 15 of the edge 10.

The upper part 17 of the inner edge of the section 5 or 6 forms a portion of the neck opening of the garment. The curved part 22 of the outer edge forms a part of the arm-hole of the garment. The intermediate portion 16 of the inner edges of the sections 5, 6 are secured together by a row of stitching 24.

Each of the sections 7, 8 is folded upon itself at its inner side and bottom and stitched together to provide inner and bottom hems 24', 25 respectively. Each of the sections 7, 8 includes a squared inner edge 26, a squared bottom edge 27 and an outer side edge formed of an inclined part 28 and an incurved part 29. The part 28 inclines outwardly from the outer end of bottom edge 27 to its point of emergence in the lower end of part 29. Each of said sections further includes a top edge 30 formed of an inclined part 30 and an incurved part 31. The part 30 inclines downwardly from the upper end of part 31 to the upper end of part 29. The part 31 extends from the inner end of part 30 and terminates in the upper end of the inner edge 26. The part 29 forms a portion of an arm opening of the garment and the part 31 forms a portion of the neck opening of the garment.

The section 7 coacts with the upper portion 55 of section 5 and the section 8 coacts with the upper portion of section 6 to provide the waist of the garment.

The top edges of sections 5, 6 are secured to the top edge parts 30 of sections 7, 8 to 60 provide shoulder straps 32. The edge parts 22 of sections 5, 6 coact with the incurved edge parts 29 of the sections 7, 8 to provide the arm openings when sections 5, 6 are secured to sections 7, 8. Bindings or pipings 33, 34 enclose the edges of the arm openings.

The upper or top edge parts of sections 5, 6 and the edge parts 31 of sections 7, 8 coact to provide the neck opening of the garment and a binding or piping 35 is not only employed to enclose the said upper or top edge parts of sections 5, 6 and the edge parts 31, but also for enclosing the inner side edges 26 of sections 7, 8, and such piping extends to the lower ends of sections 7, 8. 70

The sections 7, 8 have their inner side hems adapted to overlap. As shown, the hem of section 8 overlaps section 7 and is provided with buttonholes 36, for use in connection with upper buttons 37 and a lower button 38 carried by section 7 for detachably connecting the inner sides of sections 7, 8 together. 75

The side edges of section 9 form continuations of the outer side edges of sections 6, 7 and the said section 9 is folded upon itself at its top and secured together to provide a hem 39 provided with a series of buttonholes 40, one arranged at each end of the hem and the other centrally thereof. A button-hole 40 coacts with the button 38 for the purpose of detachably connecting the central part 80 of section 9, at its upper end to the sections 78. The section 9 is formed centrally of its bottom with an inverted, U-shaped cutout 46. The side edges 42, 43 of section 9 are substantially upon a compound curve and are oppositely disposed with respect to each other. The said side edges of the section 9 are secured for a portion of their length to the lower portion of the edge part 23 of sections 90 5, 6. The edge of the U-shaped cutout 46 is secured by stitching to the edge parts 18, 19 of sections 5, 6. The securing of the side edges of the section 9 to the edge parts 23 of the sections 5, 6 and the securing of the edge of the inverted, U-shaped cutout 46 to the edge parts 18, 19 of sections 5, 6 provide the legs 44, 45 and crotch 46' of the garment. 100

The extension members 3, 4 are in the form of two-ply rectangular strips and are secured to the upper portions of the edge parts 23 of sections 5, 6, extend inwardly therefrom and constitute flaps. The upper parts of members 3, 4 are also secured to the lower portion of the edge parts 28 of sections 7, 8. The members 3, 4 are free of connection with that part of the side edges 42, 43 of section 9 which are not secured to the edge parts 23 of sections 5, 6. That portion of section 9 which is not connected to the edge parts 23 provides a flap 47'. 110

Each of the sections 7, 8 at its lower outer corner is provided with a button 47 coacting with an outer buttonhole 40 for connecting, in connection with the button 38, the top of the flap 47' to the bottom of the sections 7, 8. 120

The lower end of each leg of the garment has arranged therein an elastic member 48 to provide for binding such end against a leg of the wearer when the garment is worn. 125

The forming of the front of the garment of 130

two sections provides for a saving in material and a decrease in cost of manufacture. The garment is of such form that it can be readily worn as an outer garment for child's use when desired or as an undergarment in combination with an outer garment, such as a child's dress, thereby providing a two-piece suit and overcoming the necessity of the child wearing a separate underwaist and a separate pair of drawers, as is the case at present. Therefore, it is thought the many advantages of a child's garment, in accordance with this invention can be readily understood, and although the preferred embodiment of the invention is as illustrated and described, yet it is to be understood that changes in the details of construction can be had which fall within the scope of the invention as claimed.

20 What I claim is:—

A child's garment of the romper type having a front and a back, said front formed of a pair of oppositely disposed sections of like contour having the intermediate portion of their inner side edges secured together, each of said sections having its inner side edge formed of an intermediate squared portion, an inwardly curved upper portion and a lower portion having an inwardly curved upper part and a squared lower part, its outer side edge formed of an upper and a lower curved portion with the latter of greater length than the former, its bottom edge squared and its upper edge of less length than the bottom edge and inclining downwardly from its inner to its outer end, said back formed of a pair of upper sections and a lower section, each of said upper sections having a portion of its top edge secured to the top edge of a front section and the lower portion of its outer side edge secured to the outer side edge of a front section, said lower section having its side edges form continuations of the outer side edges of said upper sections and the lower part of its side edges secured to the lower part of the lower portions of the outer side edges of said front sections, said lower section centrally of its bottom formed with an inverted U-shaped cutout, means for securing the edge throughout of said cutout to the lower portions of the inner side edges of said front sections to provide a crotch, means for detachably connecting the sections of the back together, and extension members 55 in the form of rectangular strips having one end thereof positioned above said lower section, said strips having their outer lengthwise edges secured throughout to the curved lower portions of the outer side edges of said front sections, the lower part of the outer side edges of said upper sections and to the lower secured part of said lower section.

In testimony whereof, I affix my signature hereto.
